UNITED STATES PATENT OFFICE.

EDWARD P. DRENNING, OF WRIGHTSVILLE, PENNSYLVANIA.

BAG OR PAPER HOLDER.

SPECIFICATION forming part of Letters Patent No. 579,566, dated March 30, 1897.

Application filed April 29, 1896. Serial No. 589,572. (No model.)

To all whom it may concern:

Be it known that I, EDWARD P. DRENNING, residing at Wrightsville, in the county of York and State of Pennsylvania, have invented a new and Improved Bag or Paper Holder, of which the following is a specification.

This invention is an improved holder or receptacle for supporting paper bags, wrapping-paper, newspapers, checks, &c., but in the drawings I have shown it as used for a bag-holder only.

The object of my invention is to provide a holder which can be made either single or double and suspended above the counter, or it can be secured to the face of wall or other fixed object.

With this object in view my invention consists in the peculiar construction of the various parts and in their combination or arrangement, all of which will be fully described hereinafter and pointed out in the claims.

In the drawings forming a part of this specification, Figure 1 is a view showing the invention in use both as a suspended holder and as one attached to the side of the wall. Fig. 2 is a detail perspective view of one-half of the suspended holder. Fig. 3 is a detail perspective view of the holder. Fig. 4 is a front view of one compartment of the holder.

In carrying out my invention for either the suspended or fixed form of holder I employ a back board A, to which a chain A' is attached in case the holder is to be suspended or through which screws A² are passed to secure the holder to the wall or other fixed object.

The bag-holder or rack B is preferably of the skeleton form and comprises the semicircular shaped-side bars C, the side brace-bars C' and C², and the top or front cross-bar D. The side bars C have their ends firmly seated in the back board A, and the ends of said side brace-bars C' C² are also seated in said back board and connect at their outer ends to the side bars C.

The top or front cross-bar D connects the two side bars, as most clearly shown, and, if desired, the upper brace-bars and the front cross-bar can all be made in one piece.

The bottom of the rack consists of the bottom bars E, seated at their inner ends in the

back board, and at their outer ends are attached to the side bars C at a point where the brace-bars C² meet the side bars, and, if desired, the bottom bars and the brace-bars C² 55 may be made in one piece, as most clearly shown.

The bottom bars E are arranged parallel within the side bars C and are curved upwardly upon the same arc, and at their upper 60 ends said bottom bars are bent outwardly at a right angle, as shown at E', in order to meet the side bars, as already described.

By arranging the side, brace, top, and bottom bars as already described it is clear that 65 I provide a skeleton rack open at the top and front and having a bottom open at the center, but capable of supporting a bag or sheet of a width greater than the space between the two bottom bars.

The bags are introduced into the rack between the top or front bar D and the back board and rest upon the bottom bars between the side and side brace-bars, as clearly shown, and in order to hold the bags or sheets compactly within the rack I employ a weight F, which is preferably connected to the front member by a bail G, pivoted at its upper end to the back board A, said bail swinging freely within the rack between the side and upper 75 brace-bars, the outward movement of said bail being limited by the top or front cross-bar D.

The bags or sheets are of course contained within the bail, as most clearly shown, and 85 as the normal tendency of the weight is to assume a perpendicular position the said bail will normally be pressed inward toward the back board, thereby keeping the bags or sheets compactly and regularly arranged upon the 90 bottom bars and against the back board.

Now whenever it is desired to remove one or more of the sacks from the rack the bottom of the sack or sheet is grasped by the thumb and finger between the bottom bars, 95 and said bag is then moved up along the curved bottom bars until it clears their ends and emerges into the opening at the front of the rack. By this operation the bail will of course be lifted, but after the bag has been 100 brought into the opening at the front of the rack it can be readily removed, and the bail

and weight will promptly drop back upon the remainder of the bags and hold them in their proper place. It will thus be seen that the bags are always held compactly within the holder without the use of pins or rods of any kind, and it is also clear that the bags can be quickly and easily removed from the holder without tearing or splitting any portion thereof.

10 The rack or holder just described can be made any size desired to accommodate paper bags or sacks, wrapping-paper, newspapers, or checks.

15 It will also be seen that the holder can be made double and suspended from the ceiling above the counter, in which instance I use a common back board A and attach holders or racks to the opposite faces thereof. The back board can also be made considerably longer 20 and a series of racks arranged side by side on each face of the board, and such racks can be made of the same or different sizes, as desired.

25 In case it is desired to make the holder stationary the board is attached to the wall or other fixed object and a series of racks attached thereto opposite each other, as most clearly shown.

While I have constructed the racks of wire 30 on account of cheapness and simplicity, it is obvious that they can be made of stronger material with slotted sides, &c., and in so

constructing the same I may employ either wood or metal.

If desired, the size or number of the bag or 35 check which is carried in the holder can be stamped or placed upon the weight, merely for the sake of convenience.

Having thus described my invention, what I claim as new, and desire to secure by Letters 40 Patent, is—

1. An improved holder, comprising a back board or base, the wire racks arranged upon each side or face of said back board or base, said racks comprising the side portions, the 45 brace-bars, the top or front cross-bar, the bottom bars right-angled in shape and arranged as described, bails pivoted to the top of the back board or base, and arranged upon opposite sides thereof, each bail carrying a 50 weight upon the forward member, substantially as shown and described.

2. An improved holder comprising the back board or base, the wire rack comprising the side and brace bars, the top or front cross- 55 bar, and the bottom bars arranged as described, the pivoted bail and the weight carried by said bail, substantially as shown and described.

EDWARD P. DRENNING.
